Application March 7, 1942, Serial No. 433,803
In Luxembourg August 4, 1939

18 Claims. (Cl. 123—46)

The present invention relates to free piston machines, that is to say machines including at least one reciprocating element the stroke or amplitude of movement of which can vary freely within certain limits, contrary to what takes place in the case of machines including connecting rods and crankshafts.

Among these machines, the invention is more especially, although not exclusively, concerned with the auto-generators of this kind, that is to say machines of the free piston type which deliver compressed air utilized, either wholly or partly, for the scavenging and the feed of the motor part of the machine, the mixture of the combustion gases and of the excess of scavenging air being fed to a receiver apparatus in which it expands, for instance a turbine.

The chief object of the present invention is to provide a machine of the type above mentioned which is better adapted to meet the requirements of practice than those used for the same purpose up to the present time.

According to an important feature of the invention, the machine of the type above set forth is devised in such manner that at least a portion of the compression work takes place during the return strokes of the reciprocating elements, and the pneumatic accumulators of energy to be included in the machine are made in such manner that they are capable of absorbing the whole of the work produced during an exceptional motive stroke of an amplitude higher than the maximum stroke corresponding with the normal running of the machine.

In a preferred embodiment of the invention, means are provided so as to be brought into play when such an exceptional stroke occurs for reducing the power developed in the motive part of the machine during the next active stroke.

According to another feature of the invention, the machine of the type above set forth being still of the kind in which at least a portion of the compression work is produced during the return stroke (taking place under the action of the pneumatic energy accumulators) of the reciprocating elements, said accumulators are made in such manner that, at least for the exceptional strokes, any increase of amplitude of the strokes of the reciprocating elements corresponds, in the compressor part of the machine, to such an increase of the amount of air that is sucked in that the compression work produced during the return stroke increases at the rate of at least one third of the increase of

energy stored up in the pneumatic accumulators during the preceding outward stroke.

According to still another feature of the invention, the starting position of the reciprocating elements is chosen at a point of their stroke which is nearer the inner end of said stroke than the outer end thereof that corresponds to the maximum amplitude admissible under normal running conditions, the pressure of the compressed air used for starting the machine being chosen in accordance with the position thus chosen for the starting of the parts.

Other features of the present invention will result from the following detailed description of some specific embodiments thereof.

Preferred embodiments of the present invention will be hereinafter described with reference to the accompanying drawings given merely by way of example, and in which:

Fig. 1 is a diagrammatical view, partly in section, of an auto-generator made according to a first embodiment of the invention;

Fig. 2 is a similar view of an auto-generator made according to another embodiment of the invention.

The following description relates, for the description of a machine of the free piston type according to the invention, to the specific case of an auto-generator of this type in which at least a portion of the compression work is produced during the return stroke of the reciprocating elements of the machine, such a case being chosen by way of example.

Concerning first the general construction of the machine, with the exception of the pneumatic energy accumulators to be included in said machine, it is of any suitable conventional or other kind, for instance such as that illustrated by Fig. 1.

In this embodiment of my invention, I provide, in a motor cylinder 1, two motor pistons 2¹ and 2², adapted to cooperate respectively, close to the outer ends of their strokes, with inlet ports 3 and outlet ports 4, respectively, the outlet ports 4 communicating with a discharge pipe 5.

Two compressor pistons 6¹ and 6² are rigidly associated with said motor pistons, respectively. The inward faces of these compressor pistons cooperate with cylinders 7¹ and 7², fitted with inlet valves 8 and outlet valves 9. The outward faces of these compressor pistons cooperate with chambers or cylinders 10¹ and 10² which constitute the pneumatic energy accumulators. The pressure in these energy accumulators depends

upon the feed pressure to be obtained from the auto-generator machine.

I provide kinematic means for synchronizing the movements of pistons 2^1 and 2^2 , these means consisting for instance of racks 11^1 and 11^2 rigid with said pistons, respectively, and both in mesh with a pinion 12 .

The fuel is fed to the motor cylinder 1 through any suitable means, for instance, as illustrated by the drawings, by means of a fuel injector 13 fed by a pump 14 actuated by a cam 15 carried by the spindle of the synchronizing piston 12 .

Cylinder 1 is surrounded by a fluidtight casing 16 , fed with air under pressure for the scavenging and the feed of the engine through the discharge valves of the compressor part of the machine.

In machines of this type, up to the present time, the pneumatic energy accumulators 10^1 and 10^2 were so dimensioned as to act only as stabilizing means, and in order to avoid any risk of the ends of said accumulators being deteriorated by pistons 6^1 and 6^2 moving beyond the normal ends of their outward strokes, safety means were provided for limiting the strokes of said pistons, said means being constituted by the synchronizing system above described.

Now, according to the present invention, the synchronizing means do not so limit the amplitude of the outward displacements of the pistons, but the energy accumulators are made capable of absorbing the whole of the motive work developed during an outward stroke of exceptional amplitude (for instance a stroke for which the whole of the scavenging air contained in cylinder 1 has combined with a great excess of fuel exceptionally injected into said cylinder).

Consequently, with such a construction, in the case of such an exceptional stroke, the pistons do not come to strike against the ends of pneumatic accumulators 10^1 and 10^2 , whereby perfect safety is ensured, and this safety is obtained without imposing any particular stress upon the synchronizing means, which can then be built much lighter than in the machines of this kind made up to this time.

It suffices, for this purpose, to give suitable dimensions to accumulators 10^1 and 10^2 and to position their ends in such manner that pistons 6^1 and 6^2 cannot touch them even at the ends of the exceptionally long strokes.

But if several exceptionally long strokes took place consecutively, the work absorbed by the compressor element might be insufficient for absorbing the excess of energy stored up in the pneumatic accumulators. In this case, the amplitudes of the successive strokes would go increasing, finally exceeding the limit value for exceptional strokes that has been reckoned upon when dimensioning the pneumatic energy accumulators.

In order to obviate this drawback, according to the present invention, I provide correcting means, adapted to be brought into play when there is an outward stroke of exceptional amplitude of the pistons, for reducing the power produced in the motor element of the machine during the next motive stroke of the pistons.

In particular, in a preferred embodiment of my invention, these correcting means act on the means for injecting fuel into cylinder 1 .

Such an arrangement is shown, by way of example, by Fig. 1.

In this construction, one of the reciprocating elements of the machine, for instance piston 6^1 ,

is provided with a push-piece 17 adapted, when the outward strokes of the pistons exceed the maximum amplitude corresponding to normal running conditions, to come into contact with a rocking lever 18 . This lever 18 is adapted to open (when so pivoted) first a valve 19 and then a valve 20 , these valves controlling two distinct compressed air circuits.

The first of these circuits is brought into play as soon as the reciprocating elements move beyond the limit position corresponding to normal running conditions and it acts upon the quantitative adjustment member 21 of the injection pump 14 . For instance, as shown by the drawing (Fig. 1), valve 19 , when opening, causes a fluid under pressure to act upon a piston 23 movable in a cylinder 22 , this piston 23 being operatively connected, through an eccentric 24 , with a link 25 adapted to control member 21 . The whole is devised in such manner that the inflow of compressed air into cylinder 22 (resulting from the opening of valve 19) corresponds to a reduction of the rate of feed of fuel pump 14 .

The second of the circuits above mentioned is arranged in such manner that the opening of valve 20 ensures the blocking of the piston of pump 14 , for instance through the action of a piston 26 sliding in a cylinder 27 , to which compressed air is fed as soon as said valve 20 is opened.

Finally, I provide cocks or the like 28 and 29 for releasing the pressures in cylinders 22 and 27 after each correcting operation.

A second example of such a correcting device is illustrated by Fig. 2.

In this example, the pivoting of rocking lever 18 produces the opening of a discharge valve 30 mounted on the delivery circuit of pump 14 .

For instance, as shown by the drawings, valve 30 is subjected to the action of a push-piece 31 one of the faces of which receives the thrust of a spring 32 which tends to keep valve 30 in the closed position thereof.

The other face of said piston 31 is subjected, when lever 18 is pivoted by push-piece 17 , to the action of compressed air, for instance by bringing a chamber 50 into communication with accumulator 10^1 through a conduit 51 , the inflow of compressed air to piston 31 being controlled by a valve 33 subjected to the action of rocking lever 18 , and the movements of said lever producing the opening of said valve 33 and, therefore, the discharge of pump 14 .

It will be readily understood that, in both of the examples above described, the correction effect is obtained as desired since the amount of fuel that is injected into the motor cylinder 1 (and consequently the power that is produced in this cylinder) is the smaller as the preceding stroke has exceeded to a greater degree the extreme position that can be admitted when working under normal conditions.

Furthermore, I have found that it is advantageous, according to the invention, to obtain that these correcting means are brought into action for an amplitude of the stroke of the pistons which depends upon one of the working characteristics of the machine, for instance the discharge pressure in casing 16 .

This result can be obtained, for instance, as follows (Figs. 1 and 2):

Said casing 16 is connected, through a conduit 34 , to a cylinder 35 with which coacts a piston 36 subjected to the action of a suitable return spring such as 37 .

This piston 36 is connected to the axis 38 about which the rocking lever 18 is pivoted, whereby a displacement of piston 36 resulting from an increase of the pressure in casing 16 produces a displacement of rocking lever 18 away from push-piece 17, which delays the action of the correcting means.

With an auto-generator made as above described, every time an outward stroke of the pistons exceeds the maximum amplitude, that is to say over reaches the limit position, admissible under normal working conditions, two consequences occur:

(a) On the one hand, an excess of energy is stored up in the pneumatic accumulators; and

(b) On the other hand, a supplementary amount of air is sucked in into the compressor elements, which supplementary amount of air produces, during the next return stroke, an excess of compression work.

It will be readily understood that, according as the working of the pneumatic accumulators is characterized by a more or less rapid rise of pressure as a function of the displacement of the pistons, the same amount of energy stored up by said accumulators may correspond to different strokes of the pistons. Therefore, the supplementary amount of air sucked in by the compressor elements when a given excess of energy is stored up by the accumulators may vary in accordance with the construction factors of said energy accumulators.

According to a feature of the present invention said energy accumulators are made in such manner that the compression work produced during the return stroke is increased at such a rate that its increase is always at least one third of the increase of works stored up in the pneumatic accumulators during the preceding outward stroke, this result being obtained by suitably choosing the ratio of the extreme pressures brought into play in said pneumatic accumulators.

Finally, the auto-generator above described is advantageously completed by providing it with starting means.

An example of such starting means is illustrated by Fig. 2.

I provide, on the end of one of the pneumatic energy accumulators, 10¹ in this case, means forming a chamber 39 communicating with said accumulator through an orifice adapted to be closed by a valve 40 coupled with a piston 41. This piston 41 is slidable in a cylinder 42 and it is fitted with a check valve 43 adapted to permit the flow of air under pressure only from cylinder 42 toward chamber 39.

Cylinder 42 is connected through a conduit 44 with a source of compressed air.

This starting device will operate in the following manner:

The pistons are first brought into a starting position which will be hereinafter defined in a more explicit manner. Then compressed air is sent into cylinder 42. This air flows past valve 43, into chamber 39, which is separated from accumulator 10¹ by valve 40. If, now, conduit 44 is opened to the atmosphere, there is produced a drop of pressure on the right hand side of piston 41, which, under the effect of the pressure existing in chamber 39, moves toward the right, and thus lifts valve 40 from its seat. The compressed air contained in chamber 39 then escaped into accumulator 10¹ and produces the

starting of the reciprocating elements of the machine.

Concerning now the starting position that the reciprocating elements must occupy, it is advantageous to determine it in advance.

This position is preferably chosen nearer to the inner end of the stroke than to the outer end corresponding to the maximum stroke admissible when the machine is running normally 10 in continuous manner. In this way, I avoid the obtainment of too important a motive work during the first outward stroke after the starting, for which stroke there is generally an excess of fuel in the feed air, and for which, furthermore, the compression work to be absorbed on the next stroke is relatively small, all these circumstances tending to give rise to motive strokes of exceptional amplitudes.

The pressure of the compressed air used for 20 starting the machine is chosen of a value sufficient for ensuring the necessary compression in cylinder 1, and this starting pressure is then higher to what would have been necessary had the starting positions of the pistons been chosen nearer to the ends of the outward strokes.

When the machine is provided with correcting 25 means such as those just above described, it is advantageous to provide means whereby said correcting means are caused to act for strokes 30 of relatively small amplitude as long as the starting period is lasting, that is to say during a certain number of reciprocations after the starting of the machine and until the latter has reached its normal thermic state. This result 35 may be obtained in the manner illustrated by Fig. 2.

In this embodiment, the source of compressed air used for starting the machine is connected, 40 with the interposition of a check valve 45 or the like, to a cylinder 46 provided with a discharge cock 47. This cylinder 46 contains a plunger piston 48 rigid with the piston 36 which carries the rocking lever 18. The whole is arranged in 45 such manner that the compressed air acting on plunger piston 48 causes rocking lever 18 to move toward push piece 17.

With such a device it will suffice, once the machine is well started, to open cock 47 for allowing rocking lever 18 freely to assume the position 50 corresponding to the working pressure existing at this time in the machine.

In order suitably to position the parts for the starting of the machine, it would be sufficient to 55 provide a mark, for instance on push piece 17, indicating the position thereof with respect to the end of accumulator 10¹. But it is preferable to provide, on the compressed air circuit serving to start the machine, safety means such that chamber 39 can be fed with compressed air only 60 when the reciprocating parts are in the correct position for starting the machine. These safety means may be constituted, for instance, by making use of push-piece 17 as a distribution slide-valve. In the example shown by the drawing (Fig. 2) an annular groove 49 is provided in said push-piece in a portion thereof which registers with conduit 44 when the reciprocating elements 65 have reached the correct starting position.

Anyway whatever be the particular embodiment that is chosen, the operation thereof results sufficiently clearly from the preceding explanations for making it unnecessary to enter into further explanations.

75 The advantages of the machines according to

the invention also result from the above description of some preferred embodiments.

Of course, the whole or a part of the arrangements above described might be applied to free piston machines other than auto-generators, and, in particular, to motor compressors in which at least a part of the compression work is effected during the return stroke of the pistons.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention, as comprehended within the scope of the appended claims.

What I claim is:

1. A free piston machine which comprises, in combination, a stationary frame, at least one reciprocating element movable with respect to said frame with an amplitude of movement variable, within given limits, in accordance with the motive action exerted on said element, means for exerting successive actions on said element in one direction, and a pneumatic energy accumulator cooperating with said reciprocating element for returning it in the other direction, said accumulator being adapted to absorb the whole of the work produced during a motive stroke of said reciprocating element of an amplitude higher than the maximum amplitude admissible under normal running conditions of the machine.

2. A free piston machine which comprises, in combination, a stationary frame, at least one reciprocating element movable with respect to said frame with an amplitude of movement variable, within certain limits, in accordance with the motive action exerted on said element, means for exerting successive motive actions on said element, in one direction, a pneumatic energy accumulator adapted to cooperate with said reciprocating element for returning it in the opposite direction, said accumulator being capable of absorbing the whole of the work produced during a motive stroke of said reciprocating element of an amplitude higher than the maximum amplitude admissible under normal running conditions of the machine, and means, operative by such an exceptional stroke of said element, for reducing the action exerted by said motive means during the next stroke, in the first mentioned direction, of said motive means.

3. A free piston machine which comprises, in combination, a motor cylinder and at least one motor piston movable therein with an amplitude of movement variable, within certain limits, in accordance with the motive action exerted on said piston, means for feeding, at intervals of time, a motive fluid to said cylinder for driving said piston in one direction, a compressor device associated with said piston adapted to perform at least a portion of the compression work during the return strokes of said piston, and a pneumatic energy accumulator associated with said piston for producing the return strokes thereof, said accumulator being capable of absorbing the whole of the work produced during a motive stroke of said piston of an amplitude higher than the maximum amplitude admissible under normal running conditions of the machine.

4. A free piston machine which comprises, in combination, a motor cylinder and at least one motor piston movable therein with an amplitude

of movement variable, within certain limits, in accordance with the motive action exerted on said piston, means for feeding, at intervals of time, a motive fluid to said cylinder for driving said piston in one direction, a compressor device associated with said piston and cylinder adapted to perform at least a portion of the compression work during the return strokes of said piston, a pneumatic energy accumulator associated with said piston for producing the return strokes thereof, said accumulator being capable of absorbing the whole of the work produced during a motive stroke of said piston of an amplitude higher than the maximum amplitude admissible under normal running conditions of the machine, and means operative by said piston on such an exceptionally long stroke thereof for reducing the feed of motive fluid to said cylinder on the next motive stroke of said piston.

5. A free piston machine which comprises, in combination, a motor cylinder and at least one motor piston movable therein with an amplitude of movement variable, within certain limits, in accordance with the motive action exerted on said piston, means for feeding, at intervals of time, air and fuel to said cylinder, whereby the combustion of said fuel in said air produces the successive motive strokes of said piston, a compressor device associated with said piston and cylinder adapted to produce at least a portion of its compression work during the return strokes of said piston, a pneumatic energy accumulator cylinder rigid with said motor cylinder and a piston rigid with said motor piston and adapted to cooperate with said accumulator cylinder so that the fluid compressed in said accumulator cylinder during the motive strokes of the motor piston produces the return strokes of said motor piston, said accumulator cylinder being so dimensioned and having its end so positioned that it is capable of absorbing the whole of the work produced during a motive stroke of the motor piston of an amplitude higher than the maximum amplitude admissible under normal working conditions of the machines, without said accumulator piston touching said end of said accumulator cylinder.

6. A free piston machine which comprises, in combination, a motor cylinder and at least one motor piston movable therein with an amplitude of movement variable, within certain limits, in accordance with the motive action exerted on said piston, means for feeding, at intervals of time, air and fuel to said cylinder, whereby the combustion of said fuel in said air produces the successive motive strokes of said piston, a compressor device associated with said piston and cylinder adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder so that the fluid compressed in said accumulator cylinder during the motive strokes of the motor piston produces the return strokes of said motor piston, said accumulator cylinder being so dimensioned and having its end so positioned that even for motive strokes of the motor piston of an amplitude higher than the maximum amplitude admissible under normal working conditions of the machine, said accumulator piston does not come into contact with said end of said accumulator cylinder, and means operative by said accumulator piston at the ends of

such exceptionally long strokes thereof, for reducing the feed of fuel to be supplied by said feeding means to said motor cylinder for the next motive stroke of said motor piston.

7. A free piston machine which comprises, in combination, a motor cylinder and at least one motor piston movable therein with an amplitude of movement variable within certain limits in accordance with the motive action exerted on said piston, said cylinder being provided with at least one inlet port for the inflow of air to said cylinder, a fuel pump, driven by said piston, for feeding fuel to said cylinder, a compressor device associated with said piston and cylinder adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder so that the fluid compressed in said accumulator cylinder during the motive strokes of said motor piston produces the return strokes of said motor piston, said accumulator cylinder being so dimensioned and having its end so positioned that, even for exceptionally long motive strokes of the motor piston, i. e., strokes of an amplitude higher than the maximum amplitude admissible under normal working conditions of the machine, said accumulator piston does not come into contact with said end of the accumulator cylinder, means for regulating said fuel feed pump, and means operative by said accumulator piston, at the end of such an exceptionally long stroke thereof, for acting on said pump regulating means so as to reduce the rate of delivery of said pump for the next motive stroke of said motor piston.

8. A free piston machine which comprises, in combination, a motor cylinder and at least one motor piston movable therein with an amplitude of movement variable within certain limits in accordance with the motive action exerted on said piston, said cylinder being provided with at least one inlet port for the inflow of air to said cylinder, a fuel pump, driven by said piston, for feeding fuel to said cylinder, a compressor device associated with said piston and cylinder adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder so that the fluid compressed in said accumulator cylinder during the motive strokes of said motor piston produces the return strokes of said motor piston, said accumulator cylinder being so dimensioned and having its end so positioned that, even for exceptionally long motive strokes of the motor piston, i. e., strokes of an amplitude higher than the maximum amplitude admissible under normal working conditions of the machine, said accumulator piston does not come into contact with said end of the accumulator cylinder, a delivery conduit for said pump adapted to convey the fuel therefrom to said motor cylinder, regulable discharge means on said conduit adapted to permit the discharge of fuel on its way to said cylinder, and means operative of fuel on its way to said cylinder, and means operative by said accumulator piston, at the end of such an exceptionally long stroke thereof, for opening more or less said discharge means so as to reduce the rate of feed of fuel to said motor

cylinder for the next motive stroke of said motor piston.

9. A free piston machine which comprises, in combination, a motor cylinder and at least one motor piston movable therein with an amplitude of movement variable within certain limits in accordance with the motive action exerted on said piston, said cylinder being provided with at least one inlet port for the inflow of air to said cylinder, a fuel pump, driven by said piston, for feeding fuel to said cylinder, a compressor device associated with said piston and cylinder and adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder so that the fluid compressed in said accumulator cylinder during the motive strokes of said motor piston produces the return strokes of said motor piston, said accumulator cylinder being so dimensioned and having its end so positioned that, even for exceptionally long motive strokes of the motor piston, i. e., strokes of an amplitude higher than the maximum amplitude admissible under normal working conditions of the machine, said accumulator piston does not come into contact with said end of the accumulator cylinder, means operative by said accumulator piston whenever its stroke exceeds the maximum admissible amplitude above mentioned for reducing the feed of fuel from said pump to said cylinder, and means operative by said accumulator piston, for strokes thereof of an amplitude exceeding a still greater value, for blocking said pump.

10. A free piston machine which comprises, in combination, a motor cylinder and at least one motor piston movable therein with an amplitude of movement variable, within certain limits, in accordance with the motive action exerted on said piston, said cylinder being provided with inlet means for the inflow of air to said cylinder, fuel feed means for supplying fuel to said cylinder, a compressor device associated with said piston and cylinder and adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder for producing the return strokes of said motor piston, said accumulator cylinder being so dimensioned and having its end so positioned that, even for exceptionally long motive strokes of the motor piston, i. e., strokes of an amplitude higher than the maximum amplitude admissible under normal conditions of work of the machine, said accumulator piston does not come into contact with said end of said accumulator cylinder, a push-piece carried by said accumulator piston and extending through said end of the accumulator cylinder, a rocking lever adapted to be pivoted by said push piece only at the end of such exceptionally long strokes of said motor piston, and means operative by said lever when so pivoted for acting on said fuel feed means so as to reduce the amount of fuel fed to said motor cylinder for the next motive stroke of said motor piston.

11. A free piston machine which comprises, in combination, a motor cylinder and at least one motor piston movable therein with an amplitude of movement variable, within certain limits, in

accordance with the motive action exerted thereon, said cylinder being provided with inlet port means for the inflow of air to said cylinder, fuel feed means for supplying fuel to said cylinder, a compressor device associated with said piston and cylinder and adapted to produce at least a portion of its compression work during the return strokes of said piston, a pneumatic energy accumulator cylinder rigid with said motor piston and adapted to cooperate with said accumulator cylinder for producing the return strokes of said motor piston, said accumulator cylinder being so dimensioned and having its end so positioned that, even for exceptionally long motive strokes of the piston, i. e., strokes of an amplitude higher than the maximum amplitude admissible under normal working conditions of the machine, said accumulator piston does not come into contact with said end of said accumulator cylinder, correcting means operated by said accumulator piston at the end of such an exceptionally long stroke thereof for acting on said fuel feed means so as to reduce the amount of fuel fed to said motor cylinder for the next motive stroke of said motor piston, and means responsive to variations of the delivery pressure of said compressor device for adjusting said correcting means in accordance with the value of said delivery pressure.

12. A free piston machine which comprises, in combination, a motor cylinder and at least one motor piston movable therein with an amplitude of movement variable, within certain limits, in accordance with the motive action exerted thereon, said cylinder being provided with inlet port means for the inflow of air to said cylinder, fuel feed means for supplying fuel to said cylinder, a compressor device associated with said piston and cylinder and adapted to produce at least a portion of its compression work during the return strokes of said piston, a casing adapted to receive the compressed fluid from said compressor device, a pneumatic energy accumulator cylinder rigid with said motor cylinder and an accumulator piston rigid with said motor piston and adapted to cooperate with said accumulator cylinder for producing the return strokes of said motor piston, said accumulator cylinder being so dimensioned and having its end so positioned that, even for exceptionally long motive strokes of the motor piston, exceeding the maximum admissible amplitude for normal working conditions, said accumulator piston does not come into contact with said end of said accumulator cylinder, a push piece carried by said accumulator piston and extending through said end of the accumulator cylinder, a rocking lever adapted to be pivoted by said push piece only at the end of such exceptionally long strokes of said motor piston, a movable support for the pivot axis of said lever, a cylinder rigid with above mentioned cylinders, a piston in said last mentioned cylinder rigid with said movable support, means for connecting the inside of the casing of said compressor device with said last mentioned cylinder, and means operative by said rocking lever for controlling said fuel feed means.

13. A free piston machine which comprises, in combination, a motor cylinder and at least one motor piston movable therein with an amplitude of movement variable, within certain limits, in accordance with the motive action exerted on said piston, means for feeding, at intervals of time, a motive fluid to said cylinder so as to obtain the motive strokes of said piston,

a compressor device associated with said piston and adapted to perform at least a portion of its compression work during the return strokes of said piston, and a pneumatic energy accumulator associated with said piston for obtaining the return strokes thereof, said accumulator being capable of absorbing the whole of the work produced by a motive stroke of said piston of an amplitude higher than the maximum amplitude admissible under normal running conditions of the machine, said accumulator being further so proportioned that the increase in the compression work of the compressor device produced during a return stroke after a motive stroke of such exceptional amplitude is at least one third of the increase of energy accumulated in said pneumatic accumulator during said exceptional motive stroke.

14. A free piston machine which comprises, in combination, a motor cylinder and at least one motor piston movable therein with an amplitude of movement variable, within certain limits, in accordance with the motive action exerted thereon, said cylinder being provided with inlet means for the inflow of air to said cylinder, fuel feed means for supplying fuel to said cylinder, a compressor device associated with said piston and cylinder and adapted to produce at least a portion of its compression work during the return strokes of said piston, a pneumatic energy accumulator cylinder rigid with said motor cylinder and accumulator piston rigid with said motor piston and adapted to cooperate with said accumulator cylinder for producing the return strokes of said motor piston, said accumulator piston being so dimensioned and having its end so positioned that, even for exceptionally long motive strokes of said motor piston, exceeding the maximum admissible amplitude for normal working conditions, said accumulator piston does not come into contact with said end of the accumulator cylinder, and means for starting the reciprocating motion of said motor piston, the starting position thereof being nearer the inner end of its stroke than the outer end thereof corresponding to the maximum amplitude admissible under normal working conditions.

15. A free piston machine which comprises, in combination, a motor cylinder and at least one motor piston movable therein with an amplitude of movement variable, within certain limits, in accordance with the motive action exerted thereon, said cylinder being provided with inlet means for inflow of air thereto, fuel feed means for supplying fuel to said cylinder, a compressor device associated with said piston and cylinder and adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder for producing the return strokes of said motor piston, said accumulator cylinder being so positioned and dimensioned that, even for exceptionally long motive strokes of said motor piston, exceeding the maximum admissible amplitude for normal working conditions, said accumulator piston does not come into contact with the end of said accumulator cylinder, means forming a chamber adjacent said accumulator cylinder, means for filling said chamber with fluid under pressure, and means for causing said fluid under pressure to pass from said chamber into

said accumulator cylinder for starting the machine, the starting position of said motor piston being nearer the inner end of its stroke than the outer end thereof corresponding to the maximum amplitude admissible under normal working conditions.

16. A free piston machine which comprises in combination, a motor cylinder and at least one motor piston movable therein with an amplitude of movement variable, within certain limits, in accordance with the motive action exerted thereon, said cylinder being provided with inlet means for the inflow of air thereinto, fuel feed means for supplying fuel to said cylinder, a compressor device associated with said piston and cylinder and adapted to produce at least a portion of its compression work during the return strokes of said piston, a pneumatic energy accumulator cylinder rigid with said motor cylinder and an accumulator piston rigid with said motor piston and adapted to cooperate with said accumulator cylinder for producing the return strokes of said motor piston, said accumulator cylinder being so positioned and dimensioned that, even for exceptionally long motive strokes of said motor piston, exceeding the maximum admissible amplitude for normal working conditions, said accumulator piston does not come into contact with the end of said accumulator cylinder, means forming a closed chamber, adapted to contain a fluid under pressure, means for causing fluid under pressure to pass from said chamber into said accumulator cylinder for starting the machine, and means operative only when said motor piston is in a predetermined position with respect to said mo- 35

tor cylinder, for permitting the last mentioned preceding means to work only for this relative position of the motor piston and cylinder, this starting position of the motor piston being nearer the inner end of its stroke than the outer end thereof corresponding to the maximum amplitude inadmissible under normal working conditions of the machine.

17. A machine according to claim 15 further including correcting means operated by the accumulator piston at the end of exceptionally long strokes thereof for acting on said fuel feed means so as to reduce the amount of fuel fed to the motor cylinder for the next stroke of the motor piston, and means for adjusting said correcting means so as to cause them to act for a smaller value of said exceptionally long strokes during the starting period of the machine.

18. A machine according to claim 15 further including a push piece carried by said accumulator piston and extending through the end of the accumulator cylinder, a rocking lever adapted to be pivoted by said push piece at the end of strokes of amplitudes exceeding a predetermined value, a movable support for the pivot axis of said lever, means operative by said rocking lever for controlling said fuel feed means so as to reduce the feed when the lever is pivoted by the push piece, and means operative by the means for filling the starting chamber with fluid under pressure for displacing said movable support toward said push piece when said chamber is filled with fluid under pressure.
